US00D947175S

(12) **United States Design Patent** (10) **Patent No.:** **US D947,175 S**
Chen (45) **Date of Patent:** **** Mar. 29, 2022**

(54) **ALL-IN-ONE COMPUTER**

(71) Applicant: **Lenovo (Beijing) Co., Ltd.**, Beijing (CN)

(72) Inventor: **Xi Chen**, Beijing (CN)

(73) Assignee: **Lenovo (Beijing) Co., Ltd.**, Beijing (CN)

(**) Term: **15 Years**

(21) Appl. No.: **29/788,523**

(22) Filed: **Jun. 17, 2021**

Related U.S. Application Data

(62) Division of application No. 29/673,602, filed on Dec. 17, 2018, now Pat. No. Des. 925,520.

(30) **Foreign Application Priority Data**

(57) **CLAIM**

The ornamental design for an all-in-one computer, as shown and described.

DESCRIPTION

FIG. 1 is a front view of all-in-one computer showing the new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines shown in the drawings illustrate portions of the all-in-one computer that form no part of the claimed design.

1 Claim, 7 Drawing Sheets
